FIG. 1 is a perspective view of a light for pool showing my new design;
 FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines throughout the drawing figures depict portions of the light for pool that form no part of the claimed design.

The unshaded surfaces between broken lines and the unshaded surfaces between solid and broken lines form no part thereof.

1 Claim, 7 Drawing Sheets(56)
